Patented Aug. 23, 1921.

UNITED STATES PATENT OFFICE.

JOHN W. COAST, JR., OF TULSA, OKLAHOMA, ASSIGNOR TO THE PROCESS COMPANY, OF TULSA, OKLAHOMA, A CORPORATION OF MARYLAND.

ART OF CRACKING HYDROCARBONS.

1,388,629.

Specification of Letters Patent. Patented Aug. 23, 1921.

Application filed September 27, 1917. Serial No. 193,472.

To all whom it may concern:

Be it known that I, JOHN W. COAST, Jr., a citizen of the United States of America, a resident of Tulsa, in the county of Tulsa, 5 State of Oklahoma, have invented certain new and useful Improvements in the Art of Cracking Hydrocarbons, of which the following is a full, clear, and exact description, reference being had to the accompanying 10 drawing, forming a part of this specification.

This invention relates to improvements in the art of cracking hydrocarbons, and more particularly to a method of treating petroleum hydrocarbons to obtain a product known as gasolene, cracked gasolene and by other names designating an explosive oil suitable for use in internal combustion engines. Some of the objects of the invention 15 are to avoid the danger, expense and loss of time usually due to the presence of coke-forming matter in cracking stills; to economize in the use of fuel, and to utilize the hot fluid discharged from a cracking coil 20 as a heating medium for the liquid contents of a still. Another object is to maintain the apparatus in continuous operation for a considerable period of time, without removing the coke-forming matter.

In the preferred form of the invention a 25 body of hydrocarbon oil is maintained in a large cylindrical cracking still, and the hot fluid discharged from a cracking coil is utilized to heat said body of oil. The contents 30 of the cracking coil are preferably subjected to a very high degree of heat and forced into the body of oil in the cylindrical still, the vapor passing from said coil being permitted to bubble through said body of oil. The 35 liquid contents of the cylindrical still are thus commingled with and heated by the hot fluid discharged from the coil. The temperature of this fluid is so high that the desired cracking takes place in the still without 40 transmitting the usual high degree of heat through the metal of the still. As a result, the transmission of heat to the body of oil is not greatly affected by the presence of coke 45 on the still bottom, and the danger usually 50 due to overheating a cylindrical still is almost entirely eliminated. Furthermore, the losses due to the transmission of heat through a body of coke are minimized for the coke on the still bottom does not in any way 55 interfere with the transmission of heat from

the preheated fluid to the body of oil. This hot fluid also increases the efficiency of the apparatus by circulating the liquid in the still. By eliminating the danger of overheating the cylindrical still, and at the same 60 time subjecting the oil to the necessary high temperature, the apparatus can be operated continuously for a considerable period of time.

To fully appreciate a most important feature of this invention, it will be necessary to understand that some oils can be cracked more readily than others. High boiling point oils can be easily cracked to produce gasolene, but the same is not true of lighter 70 oils, such as distillates of the illuminating oil series. For example, high boiling point oils, such as gas oil and fuel oil, can be very successfully cracked in a large cylindrical cracking still at a temperature of about 750° 75 F. and a pressure of about 85 pounds per square inch, whereas lighter oils, such as distillates of the illuminating oil series, must be subjected to higher pressures and higher temperatures. In actual practice, I have 80 found that it is economical and otherwise desirable to crack the high boiling point oils in a large fire heated cylindrical cracking still, and that lower boiling point oils of the illuminating oil series can be very success- 85 fully cracked in a cracking coil maintained at a relatively high pressure and at a correspondingly high temperature. According to the present invention, high boiling point oils and low boiling point oils are 90 cracked simultaneously, and each body of oil is subjected to the conditions most favorable for the conversion of its constituents into cracked gasolene. The high boiling point oil, preferably gas oil or fuel oil, is cracked 95 under pressure in an ordinary cylindrical still. The low boiling point oil, preferably a distillate of the illuminating oil series, is subjected to a higher pressure and to a higher temperature, and then discharged 100 into the cylindrical cracking still. The different oils are thus subjected to most desirable conditions, and the fluid discharged from the hottest still is forced into the oil undergoing distillation at a lower temperature in the cylindrical still.

The drawing is a diagrammatical view of a cracking apparatus adapted for use in carrying out the new method.

To illustrate the invention I have shown a 110

cracking apparatus comprising a large horizontal cylindrical cracking still 1 arranged above a heating chamber 2, a vapor pipe 3 leading from said still to an air cooled reflux condenser 4, a second reflux condenser 4' arranged to receive the vapor flowing from the condenser 4, and a vapor pipe 5 connecting said reflux condenser 4' to a water cooled condenser 6 from which the product is recovered. A pressure regulating valve 7, preferably located in the vapor pipe 5, may be regulated to maintain a predetermined pressure in the reflux condensers and still 1. In the reflux condensers, the fractions having relatively high boiling points are condensed and separated from the lighter fractions which pass to the main condenser 6. The high boiling point condensate formed in the reflux condensers, flows into a pipe 8 whereby it is conducted back to the still 1.

A perforated discharge pipe 9, submerged in the lower portion of the still 1, is connected by means of a pipe 10 to the discharge end of a fire heated cracking coil 11, the latter consisting of a coil of pipe arranged within a furnace or heating chamber 12.

The apparatus herein shown is particularly adapted for use in cracking distillates or residues resulting from the distillation of petroleum. A body of hydrocarbon oil is maintained in the large cylindrical still 1, and this oil is maintained at a cracking temperature, partly by the heat transmitted from the fire in the heating chamber 2, and partly by streams of hot fluid discharged from the perforated pipe 9. A fresh charge of oil is conducted through a pipe 13 to a pump 14, which forces the oil through a pipe 15 and into the cracking coil 11. Steam passing from a pipe 16 is discharged into the pipe 15 where it commingles with the oil flowing into the coil. The mixture of steam and hydrocarbons is forced through the coil at a high velocity and discharged into the pipe 10 leading to the perforated pipe 9 at the bottom of the cylindrical still.

It will be observed that the structure herein shown comprises a primary cracking apparatus including the cracking coil 11, a secondary cracking apparatus including a large still 1, and a condenser 6 common to the primary and secondary cracking apparatus.

The oil introduced into the cracking coil may be a distillate of the illuminating oil series having a boiling point of about 500° F., and a gravity of about 42° Bé., and the body of oil introduced into the large cylindrical still 1 may be a fuel oil, or a gas oil having a gravity of about 32° Bé. and a boiling point of about 600° F. In other words, I preferably introduce a "low" boiling point distillate into the cracking coil and a "high" boiling point distillate into

the cylindrical still 1. A fresh charge of the high boiling point oil may be forced from a supply pipe 18 through a pump 19 and thence through a pipe 20 to the pipe 10 leading into the still 1. To successfully crack the "low" boiling point oil, it is necessary, or desirable, to use extremely high pressures and temperatures, and it would be dangerous and uneconomical to operate the large cylindrical still 1 under such pressures and temperatures. However, the small tubes forming the cracking coil 11 can withstand a much higher pressure and a much higher temperature than the large cylindrical still. It is, therefore, an advantage to maintain the contents of the cracking coil under a higher pressure and at a higher temperature than the cylindrical still. The difference in pressure can be obtained by adjusting a valve 21 in the pipe 10 leading from the cracking coil to the cylindrical still.

The contents of the cracking coil may, for example, be subjected to the pressure of about 150 pounds per square inch, and a temperature of about 900° F., while the contents of the cylindrical still 1 are maintained at a pressure of about 85 pounds per square inch and a temperature of about 750° F. It will, of course, be understood that the invention is not in any way limited to the use of any specific pressure, nor to any particular temperature, but it is important to observe that the "low" boiling point oil in the cracking coil is subjected to a higher pressure and to a higher temperature than the pressure and temperature of the "high" boiling point oil in the large cylindrical still. The reasons for these differences in pressure and temperature have already been pointed out.

The vapor discharged from the cracking coil at a very high temperature bubbles through the body of oil in the cylindrical still, and serves as a very effective heating medium for the oil. By transmitting heat to the interior of the cylindrical still in this manner, a lower fire can be used under the cylindrical still, thus economizing in the use of fuel and avoiding the danger of overheating the bottom of the cylindrical still.

I claim:

1. In the art of cracking high boiling point and low boiling point hydrocarbon oils, the method which comprises maintaining a body of the high boiling point oil in a cracking still, forcing the low boiling point oil into a cracking coil, discharging the contents of the cracking coil into said high boiling point oil in the still, maintaining the low boiling point oil under a relatively high pressure and at a relatively high temperature, and maintaining the high boiling point oil under a lower pressure and at a lower temperature.

2. In the art of cracking high boiling

- point and low boiling point hydrocarbon oils, the method which comprises maintaining a body of the high boiling point oil in a large cylindrical cracking still, forcing 5 the low boiling point oil into a cracking coil, subjecting the high boiling point oil in the cylindrical still to a cracking temperature and a cracking pressure, subjecting the low boiling point oil in the cracking 10 coil to a pressure and temperature higher than that of the cylindrical still, and at the same time discharging the cracked product from the cracking coil and into the oil in said cylindrical still.
- 15 3. In the art of cracking high boiling point and low boiling point hydrocarbon oils, the method which comprises maintaining a body of gas oil in a cracking still, forcing a distillate of the illuminating oil 20 series into a cracking coil, discharging the contents of the cracking coil into the oil in said still, maintaining the distillate of the illuminating oil series under a relatively high pressure and at a relatively high temperature, and maintaining the gas oil under 25 a lower pressure and at a lower temperature.
4. In the art of cracking high boiling point and low boiling point hydrocarbon oils, the method which comprises maintaining a body of the high boiling point oil in 30
- a large cylindrical cracking still, forcing a low boiling point oil of the illuminating series into a cracking coil, subjecting the high boiling point oil in the cylindrical still to 35 a cracking temperature and a cracking pressure greater than 50 pounds per square inch, subjecting the low boiling point oil of the illuminating series in the cracking coil to a pressure and temperature higher than that 40 of the oil in the cylindrical still, and at the same time discharging the cracked product from the cracking coil and into the oil in said cylindrical still.
5. In the art of cracking high boiling 45 point and low boiling point hydrocarbon oils, the method which comprises maintaining a body of the high boiling point oil in a cracking still, forcing the low boiling point oil into a cracking coil, commingling 50 steam with the low boiling point oil in the cracking coil, discharging the contents of the cracking coil into the oil in said still, maintaining the steam and low boiling point oil under a relatively high pressure and at 55 a relatively high temperature, and maintaining the high boiling point oil under a lower pressure and at a lower temperature sufficient for cracking.

In testimony that I claim the foregoing 60 I hereunto affix my signature.

JOHN W. COAST, JR.
